UNITED STATES PATENT OFFICE.

ORRA L. GILLILAND, OF MINNEAPOLIS, MINNESOTA, ASSIGNOR TO NATIONAL SHOCK LOADER CO., OF MINNEAPOLIS, MINNESOTA, A CORPORATION OF SOUTH DAKOTA.

LOADER.

1,397,956.

Specification of Letters Patent.

Patented Nov. 22, 1921.

Application filed November 2, 1917. Serial No. 199,955.

To all whom it may concern:

Be it known that I, ORRA L. GILLILAND, a citizen of the United States, residing at Minneapolis, in the county of Hennepin and 5 State of Minnesota, have invented certain new and useful Improvements in Loaders; and I do hereby declare the following to be a full, clear, and exact description of the invention, such as will enable others skilled in 10 the art to which it appertains to make and use the same.

My invention relates to loaders for use in loading bundles, shocks, hay, and the like, and is in the nature of an improvement on 15 my copending application entitled "Loader," filed July 17, 1916, under S. N. 109,628.

To the above end, the invention consists of the novel devices and combinations of devices hereinafter described and defined in 20 the claims.

In the accompanying drawings, which illustrate the invention, like characters indicate like parts throughout the several views.

25 Referring to the drawings,

Figure 1 is a longitudinal vertical section taken on the line 1—1 of Fig. 2 and illustrating the front end portion of the loader, some parts of which are shown in different 30 positions by means of broken lines;

Fig. 2 is a view, principally in plan, illustrating the parts shown in Fig. 1, with some parts removed and other parts sectioned;

Fig. 3 is a fragmentary detail view in section taken on the irregular line 3—3 of Fig. 2, on an enlarged scale;

Fig. 4 is a perspective view of one of the side plates and connecting tie bars;

Fig. 5 is a fragmentary detail perspective 40 view of the pickup device;

Fig. 6 is a front end elevation of substantially one-half of the loader, on an enlarged scale; and

Fig. 7 is a plan view of the parts shown 45 in Fig. 6.

The main frame of the loader, at its rear portion, is supported on a pair of traction wheels, not shown, and includes a pair of forwardly and downwardly projecting side 50 channel bars, the front end portions of which are bent to project substantially horizontal. These side bars 7 are rigidly connected at their angles by an angle tie

bar 8. Other tie bars and braces will be provided for further rigidly connecting the side 55 bars 7 rearward of the tie bar 8, but, for the purpose of this case, it is not thought necessary to illustrate the same.

A supplemental frame, located directly under the front horizontal end of the main 60 frame, comprises a pair of channel side bars 9, the rear ends of which are pivoted at 10 to plates 11, formed by bending the ends of the tie bar 8 and rigidly securing the same to the side bars 7 of the main frame. 65 These pivots 10 permit raising and lowering movement of the rear end of the supplemental frame, with respect to the main frame, and to be supported in different elevations above the ground. 70

Rigidly secured to the forward end of each side bar 9 of the supplemental frame, is a wheel bracket 12 having integrally formed therewith a vertical sleeve-bearing 13, in which is rotatively mounted an upright front wheel steering post 14. These steering posts 14 have their lower ends rigidly secured to the inner ends of stub axles 15 on which are journaled a pair of front wheels 16. The lower ends of the 80 bearings 13 rest on shoulders 17 on the stub axles 15 and support the wheel brackets 12, and hence, the front end of the loader from the front wheels 16.

To each wheel bracket 12, is rigidly secured the lower ends of a pair of laterally spaced upright angle posts 18. These four posts 18 are laterally spaced transversely of the loader and rigidly connected at their upper ends by a channel tie bar 19. The 90 ends of this tie bar 19 extend outward of the pairs of posts 18 and have rigidly secured thereto brackets 20, in which the upper ends of the wheel posts 14 are journaled. These brackets 20 are also rigidly secured to the 95 posts 18. Diagonal angle brace bars 21 rigidly connect the inner posts 18 to the tie bar 19.

To each wheel post 14, above the respective bracket 20, is rigidly secured a rearwardly projecting arm 22 and to the right hand wheel post 14, is also rigidly secured an inwardly projecting toothed segment 23. A tie rod 24 connects the two arms 22 for simultaneous movement. Steering movement is imparted to the front wheels 16 by 100 105

a worm 25 meshing with the segment 23 and which worm also locks the wheels 16 where set. The worm 25 is secured to the front end of a long steering rod 26, which extends to 5 the rear of the loader and is preferably operated by a hand wheel, not shown. Obviously, the shoulders 17 and hubs of the arms 22 hold the wheel posts 14 against endwise movement in their bearings 13 and 20.

10 A neck yoke evener is carried by the wheel posts 14 and comprises a pair of angle brackets 27, having their horizontal members turned outward and their vertical members turned upward. The vertical members 15 of the brackets 27 are in the form of long sleeves 28, through which the wheel posts 14 project. Collars 29, on the wheel posts 14, engage the lower ends of the sleeves 28 and support the brackets 27 with freedom 20 for swinging movement in a horizontal plane and with the upper ends of said sleeves in engagement with the bearing brackets 20. Horizontally elongated apertures 30 are formed in the outer ends of the horizontal 25 members of the brackets 27 to receive neck yoke straps, not shown. Integrally formed with the upper ends of the sleeves 28, is a pair of forwardly projecting arms 31 connected by a tie or equalizing rod 32.

30 The forward ends of the side bars 7 of the main frame project between the pairs of posts 18 and are supported therefrom, for raising and lowering movement, with respect to the forward end of the supplemental 35 frame, by bell crank levers 33, links 34 and operating rods 35. The bell crank levers 33 are located between the pairs of posts 18 and secured thereto by pivot bolts 36. One of the arms of the bell crank levers 40 33 projects forwardly and upwardly and has the forward ends of the operating rods 35 pivoted thereto. The other ends of the bell crank levers 33 project forwardly and downwardly and have the upper ends of the links 45 34 pivotally attached thereto. The other or lower ends of the links 34 are connected to the side bars 7 by eye-bolts 37. Suitable mechanism, including a latch lever, not shown, will be provided for connecting the 50 rear ends of the rods 35, for imparting simultaneous endwise movement thereto and for holding the same where set.

To facilitate the raising of the front end of the main frame, counterbalancing springs 55 38 are provided. The lower ends of these springs 38 are anchored to the wheel brackets 12 of the supplemental frame and their upper ends are connected by links 39 to rearwardly and upwardly projecting arms 40 integrally formed with the bell crank levers 33.

Mounted within the main and supplemental frames, are two vertically disposed and laterally spaced cast side plates 41 rigidly connected and held properly spaced, at 60 their rear ends, by an angle tie bar 42 and,

at their intermediate portions, by angle tie bars 43. The side plates 41 are intermediate and pivotally supported for vertical swinging movement by a pair of axially aligned tubular trunnions 44, integrally 70 formed with the outer faces thereof and journaled in bearings 45 on the side bars 9 of the supplemental frame. It will be noted that the trunnions 44 are located considerably rearward of the longitudinal centers 75 of the side plates 41, so that the forward ends thereof will tend to tip downward.

The forward ends of the side plates 41 are supported, at the desired elevation above the ground, by a pair of short chains 46 80 and a pair of rods 47. One of the ends of the chains 46 is anchored to the front ends of the side plates 41 and their other or upper ends are attached to the forward ends of the rods 47. The intermediate portions 85 of the chains 46 are arranged to run over grooved guide wheels 48 journaled on the inner faces of the side bars 7 of the main frame. Suitable mechanism, preferably foot-actuated, not shown, will be provided 90 for connecting the rear ends of the rods 47, imparting endwise movement thereto and holding the same where set. It may be here stated, that one of the purposes of the short chains 46 is to provide a flexible connection, 95 whereby the forward ends of the side plates 41 may lift, in case either one thereof engages an obstruction.

Formed with each side plate 41 and spaced inward therefrom is an endless flat track 100 49 positioned in a vertical plane with its outer edges connected by a vertical web 50. The upper and lower sections of the track 49, at their forward ends, come together in the form of a downwardly inclined V. The 105 upper section of the track 49 has on its inner face a forwardly and downwardly inclined cam surface 51, the lower end of which is connected to the upper member of the V by a horizontal surface 52. Also 110 formed in the upper section of the track 49, is a downwardly and rearwardly inclined cam surface 53. In the lower section of the track 49, under the track surface 52, is a cam surface 54.

Between the side plate 41 and web 50, is a wheel pocket 55 that is concentric with the trunnion 44. On the lower edge of the side plate 41, is an inwardly projecting horizontal flange 55', the rear end of which runs 120 into the bottom and rear wall of the wheel pocket 55 and forms an extension thereof. Extending transversely through the upper and lower sections of the track 49 and through the web 50, is a passageway 56.

A track section 57 forms a forward continuation of the rear portion of the lower section of the track 49. The track 57, where the same joins the track 49, is curved and formed by widening the flange 55'. The 130

outer portion of the track 57 is straight and extends forwardly and downwardly in a plane below the adjacent portion of the flange 55', and is substantially parallel therewith. Between the curved and straight portions of the track 57, is a right angle drop or depression 58.

Mounted in each wheel pocket 55, is a pair of integrally formed sprocket wheels 59 and 60 journaled on a short shaft 61, having its outer end journaled in the hollow trunnion 44 and its inner end in a seat 62 formed in the web 50. Alined with each sprocket wheel 59, is a relatively small sprocket wheel 63 journaled on a movable bearing 64, adjustably secured to the front end of the side plate 41, and which bearing acts as a chain tightener for a sprocket chain 65 arranged to run over the alined sprocket wheels 59 and 63. The upper and lower laps of each sprocket chain 65 are held spaced apart by a large smooth faced wheel 66, located between the side plate 41 and web 50 and journaled on a short shaft 67 mounted in seats formed in the side plate 41 and web 50.

Several sets of pickup devices or forks, as shown three, are mounted on the loader and moved in an endless course by the sprocket chains 65. Each set of pickup devices comprises a plurality of tines 68, a horizontal tubular bar 69 and a pair of arms 70, to the intermediate portions of which are rigidly secured the ends of said bar. The tines 68 are detachably but rigidly secured to the bar 69 by laterally spaced holders 71 integrally formed therewith and have curved channel-shaped front end portions and tubular rear end portions to receive the rear ends of the tines. Cotter pins 72 are, as shown, provided for holding the tines 68 in their holders 71, but, of course, nuts or other securing means may be provided.

The short or front ends of the arms 70 are secured to the sprocket chains 65 by long pivot pins 73, on the intermediate portions of which are journaled rollers 74. These rollers 74 also act as spacing devices for the chains 65 and arms 70. Relatively short rollers 75 are journaled on trunnions secured to the rear or long ends of the arms 70, project in the same direction as the rollers 74, and are arranged to run over the inner face of the endless track 49. Integrally formed with the rear portion of each arm 70, is an offset and upwardly projecting cam flange 76. These cam flanges 76 are offset inward from the arms 70, project thereabove and are provided for a purpose that 60 will presently appear.

During the rearward travel of the pickup devices or forks, the rollers 75 move over a track surface afforded by the upper face of the upper section of the track 49 and are

held in contact therewith, except at the 65 passageway 56, under the action of the weight or load on said forks. While the rollers 75 are moving through the passageways 56, the free or rear ends of the arms 70 are held by the engagement of the cam 76 flanges 76 with small rollers 77. These rollers are journaled on brackets 78 carried by an angle tie bar 79 rigidly secured at its end to the upper edges and intermediate portions of the side plates 41. This tie 75 bar 79 also assists the tie bars 42 and 43 in rigidly connecting the side plates 41. The engagement of the cam flanges 76 with the rollers 77 prevent the forks from tipping downward, under the weight of the load 80 thereon.

A deck, comprising a plurality of edge-wise spaced plates 80, extends from the front ends of the side plates 41 to the tie bar 79. The lower ends of the deck plates 80 are 85 folded backward and extend, for a considerable distance, toward the tie bar 43. Each deck plate 80 is independently secured in position by having its longitudinal edges folded around rods 81, the upper ends of which are 90 anchored to the tie bar 79 and the lower ends of which are attached to the tie bar 43. It will be noted that the end portions of the rods 81, from points where they leave the deck plates 80, are spread horizontally to 95 brace said deck plates. The spacing of the deck plates 80 is such that the tines 68 of the pickup devices work freely therebetween.

The pickup devices are preferably positioned to move over the surface of the 100 ground, substantially at the same elevation in which the cut of the grain or hay is made. To gather the materials below this elevation, I provide a multiplicity of laterally spaced rake fingers 82, which extend transversely across the loader, at the extreme front ends of the side plates 41. There is a pair of these rake fingers 82 secured to each deck plate 80 and the tines 68 passed between the several pairs thereof and pick 110 up the materials, such as straw and hay accumulated thereby. To permit the rake fingers 82 to yield, in case they engage obstructions, such as stones, stumps, or rough places in the field, the same are provided 115 with spring coils 83 located in the curved front ends of the deck plate 80. From these coils 83, the rake fingers 82 extend downwardly and rearwardly, and hence, curve 120 forwardly, so that their sharp ends are positioned quite close to the surface of the field.

An elevator is provided for receiving the bundles or other materials delivered thereto by the pickup devices. This elevator comprises a pair of endless sprocket chains 84 125 and a multiplicity of spaced slats 85, in the form of angle bars, with one of their flanges secured to the sprocket chains and pro-

jecting in the direction of the travel thereof, and their other flanges projecting inwardly. The inwardly projecting flanges of the slats 85, on the upper lap of the sprocket chains 84, scrape over a flat deck 86 secured to side boards 87. The lower ends of the side boards 87 are rigidly secured by castings 88 to the upper flanges of the side bars 7 of the main frame and the upper ends 10 thereof are supported on framework, not shown, carried by the main frame. The sprocket chains 84 run over upper and lower pairs of sprocket wheels, only the lower of which are shown and indicated by the reference numeral 89. These sprocket wheels 89 are journaled on a transverse shaft 90, having its ends mounted in the castings 88.

The sprocket chains 65 of the pickup devices are driven from the elevator by a pair 20 of short sprocket chains 91, which run over the sprocket wheels 60 and alined relatively small sprocket wheels 92 integrally formed with the sprocket wheels 89 and journaled on the shaft 90. The elevator is driven, 25 in the direction of the arrows marked thereon in Fig. 1, by suitable connections, not shown, from the traction wheels of the loader to the upper sprocket wheels of said elevator. The loader may be propelled by 30 a gas engine mounted thereon, or pushed or pulled by a tractor or draft animals.

Longitudinal brace angle bars 93 connect the upper ends of the posts 18 with the intermediate portions of the side bars 87. 35 These brace bars 93 securely hold the upper ends of the posts 18 against forward and backward movement, but to permit the required raising and lowering movement of the supplemental frame, their forward ends 40 are pivotally attached to the castings 20 and their rear ends are pivotally attached to the side boards 87.

The operation of the improved loader may be briefly described as follows:—

45 By manipulating the rods 35, the operator may raise or lower the forward end of the main frame and thereby simultaneously impart a like movement to the rear end of the supplemental frame, as indicated by broken lines in Fig. 1. With this adjustment of the supplemental frame, the side plates 41 are bodily carried therewith, together with the pickup devices or forks. It will thus be seen that the pickup devices may be set, so 50 that their tines 68, during the lower lap of their travel, will be at the desired elevation above the ground. Then by manipulating the rods 47, the operator may oscillate the side plates 41 to properly position the tines 68. Obviously, by drawing rearward on the rods 47, the forward ends of the side plates 55 41 may be raised, so that they, or the tines 68 and rake fingers 82, will clear an obstruction. As previously stated, the flexible 60 connections or chains 46 will permit the

forward ends of the side plates 41 to raise, in case they, or the tines 68, engage an obstruction, and thus prevent the pickup devices from being damaged or broken. If one of the tines 68 or rake fingers 82 are 70 broken or bent, the same may be readily replaced with a new one.

It will be noted that the wheels 66 hold the sprocket chains 65, so that they move in substantially diamond-shaped courses. 75 When the sprocket chains 65 are making their lower lap of travel, the rollers 75 move on the inner faces of the lower sections of the tracks 49 and, when making their upper lap of travel, said rollers move on the inner 80 faces of the upper sections of said tracks. Also, during the lower lap of travel of the sprocket chains 65, the rollers 74 move on the flanges 55 and, during their upper lap of travel, said rollers move on the upper 85 faces of the upper sections of the tracks 49. It will also be noted that the rollers 74 move in the same endless diamond-shaped courses with the sprocket chains 65 and carry the front ends of the arms 70 there- 90 with, while the rollers 75 move back and forth in substantially a horizontal course, but at different elevations. It will thus be seen that the rearwardly moving pickup devices move bodily over the forwardly 95 moving pickup devices.

At the beginning of the forward movement of the pickup devices, the arms 70 are in substantially horizontal positions and the tines 68 are completely withdrawn from 100 between the deck plates 80 and their points project upwardly. As the sprocket chains 65 move under the sprocket wheels 59 and toward the wheels 66, the tines 68 are brought into substantially horizontal positions. 105 Further movement of the sprocket chains 65 will cause the tines 68 to move bodily between the rearwardly projecting ends of the deck plates 80 and progressively tip toward the ground, until they pass under 110 the wheels 66, at which points said tines pass between the pairs of rake fingers 82 and pick up the top of the load accumulated thereby. Under the advance movement of the sprocket chains 68 from the wheels 66, 115 the tines 68 are bodily and gradually lifted and just before the rollers 74 reach the sprocket wheels 63, the rollers 75 engage the cam surfaces 54, which abruptly throw the points of the tines 68 downward and further advance movement thereof causes said tines to enter a bundle or shock or pick up loose materials on the ground. As the rollers 74 pass around the sprocket wheels 63, the rollers 75 stand substantially still, 120 while the points of the tines 68 are gradually lifted with the load. The upward movement of the rollers 75 on the cams 54 carries the same onto the track surfaces 52.

During the upper lap of travel of the 130

sprocket chains 65, the weight of the load will tend to tip the tines 68 downward, and thereby hold the rollers 75 onto the upper sections of the tracks 49. While the rollers 74 are moving upward from the sprocket wheels 63 to the wheels 66, the points of the tines are still gradually lifted to insure the safe delivery of the load over the deck plates 80 to the elevator. After the rollers 74 have passed over the wheels 66, the tines 68 start to recede and are gradually withdrawn from the load and from between the deck plates 80.

The purpose of the passageways 56 is, of course, to permit the connections between the sprocket chains 65 and arms 70, to wit:—the pivot pins 73 and rollers 74, to pass through the tracks 49. To carry the rollers 75 across the passageways 56, during their rearward movement, there are provided the rollers 77, with which the cam flanges 76, on the arms 70, engage and hold the rear ends of said arms against lifting movement. In the forward movement of the rollers 75, they are carried across the passageways 56 by the track extensions 57, including the bottom of the depressions 58. These track extensions 57 project inward from the tracks 49, sufficiently to be engaged by the curved lower edges of the arms 70 at points directly under the bars 69. Obviously, with the intermediate portion of the arms 70 on the track extensions 57 and the rollers 74 on the tracks 49, said arms will be held against vertical swinging movement, and thereby carry the rollers 75 across the passageways 56. When the pickup devices are traveling without a load, the overbalanced rear ends thereof will tend to tip downward.

To further guide the rear ends of the arms 70 over the tracks 49 and across the passageways 56, the spacing of the upper and lower sections of said track are such that the oppositely moving arms 70, during the intermediate portion of their travel each way, slide, the one upon the other, and act as track sections, which hold the rollers 75 and the tracks 49 and prevent swinging movement of the arms 70 in crossing the passageways 56.

By positioning the tines 68, so as to pick up only the top of the load accumulated by the rake fingers 82, all stones gathered by said fingers will be left on the ground and work their way through the rake fingers, or, in case the stones are too large to pass therebetween, said fingers will yield and pass over the same.

In picking up a shock, the advance set of tines 68 will enter the nearest bundle or bundles and force the butt end or ends thereof into the shock and, at the same time, lift the same, which will tend to tip the tops of the bundles toward the loader. The next advancing set of tines 68 will enter the bundle

or bundles of the next nearest shock and force their butt ends into the shock and, at the same time, lift the same and tip their top or tops onto the first lifted shock. This action is repeated until all of the bundles of a shock are picked up. The importance of first forcing the butts of the bundles into a shock is to hold any loose grain therein, or which may be shelled, during the picking up of a shock. In case any loose grain falls onto the deck 86, at the time the bundles are delivered from the pickup devices to the elevator, or while the bundles are being moved upward by the elevator, the same will be collected by the slats 85 and scraped upward thereby on the deck 86 and delivered onto a conveyer, not shown. Such a conveyer would preferably be arranged to carry the materials delivered thereto, by the elevator, into a basket rack on a vehicle driven at one side of the loader. The elevator will, of course, handle also all kinds of materials delivered thereto, whether loose or in bundles, and bundles projecting between the slats of the elevator will sweep the deck 86, and thereby assist in carrying all loose materials thereon to the conveyer.

It will be noted that the trunnions 44 are so positioned that the forward ends of the side plates 41 tip downward, when the pickup devices are traveling idle without a load. It will also be noted that the pull on the sprocket chains 91 over the sprocket wheels 60 is in a direction, which tends to lift the forward ends of the side plates 41 and thereby substantially balance the same, so that there is very little pull on the connections 46 and 47. In case the tines 68 engage an obstruction, or the load being accumulated thereby is such as to cause the sprocket chains 65 to drag, the increased pull on the sprocket chains 91 will lift the forward ends of the side plates 41, and hence, the respective tines 68, and thereby cause the same to clear the obstruction or move out of the load being accumulated.

The above described loader has, in actual usage in the field, proven highly efficient for the purpose had in view. By the use of the rake fingers 82, the field is raked clean, thus preventing any waste. From actual inspection of the field, under a multiplicity of shocks, after they had been picked up, practically no loose grain was found.

What I claim is:—

1. In a loader of the kind described, the combination with a truck, of a pair of endless chains mounted on the truck and means for driving the same, a pickup device including a pair of carrying arms, connections attaching one end of the carrying arms to the chains, upper and lower tracks vertically spaced to afford channels in which the other or free ends of the carrying arms extend for travel on the tracks, upper and lower track 130

- surfaces on which said connections travel, and vertical passageways in the channels through which the connections move from the upper track surfaces to the lower track surfaces.
2. In a loader of the kind described, the combination with a truck, of a pair of endless chains mounted on the truck and means for driving the same, a pickup device including 10 a pair of carrying arms, connections attaching one end of the carrying arms to the chains, upper and lower tracks vertically spaced to afford channels in which the other or free ends of the carrying arms extend for 15 travel on the tracks, upper and lower track surfaces on which said connections travel, vertical passageways in the channels through which the connections move from the upper track surfaces to the lower track surfaces, 20 and means for guiding the free ends of the arms across the passageways.
3. In a loader of the kind described, the combination with a truck, of a pair of endless chains mounted on the truck and means for 25 driving the same, a plurality of sets of pickup devices each having a pair of carrying arms, connections attaching one end of the arms to the chains, upper and lower tracks vertically spaced to afford channels 30 in which the other or free ends of the carrying arms extend for travel on the tracks, upper and lower track surfaces on which said connections travel, and vertical passageways in the channels through which the connections move from the upper track surfaces to the lower track surfaces, said pairs of carrying arms alternately acting as track sections for the other of said arms during 35 certain portions of their travel.
4. In a loader of the kind described, the combination with a truck, of a pair of endless chains mounted on the truck and means for driving the same, a plurality of sets of pickup devices each having a pair of carrying 40 arms, connections attaching one end of the arms to the chains, upper and lower tracks vertically spaced to afford channels in which the other or free ends of the carrying arms extend for travel on the tracks, 45 upper and lower track surfaces on which said connections travel, vertical passageways in the channels through which the connections move from the upper track surfaces to the lower track surfaces, said pairs of carrying arms alternately acting as track 50 sections for the other of said arms during certain portions of their travel, cam flanges on the carrying arms, and rollers with which said cam flanges engage for holding said 55 arms during their travel through the passageways.
5. In a loader of the kind described, the combination with a truck, of a pair of side plates intermediately pivoted on the truck 60 for vertical swinging movement, means for 65 moving the side plates and holding the same in different positions, and a pickup device mounted on the side plates to travel an endless course.
6. In a loader of the kind described, the combination with a truck having a frame, of side plates intermediately pivoted to the frame for vertical swinging movement, a pickup device carried by the side plates, flexible connections for moving the side 70 plates on their pivots and for holding the same in different set positions, said connections arranged to permit the side plates to move on their pivots to clear an obstruction.
7. In a loader of the kind described, the combination with a truck having a frame, of side plates pivoted to the frame, means for holding the side plates on their pivots, whereby their front ends are free to lift and 75 then return to normal position, a pair of endless chains mounted on the side frames, means for driving the chains, including a wheel at the axis of the pivots of the side frames and a belt arranged to run over said 80 wheel, the pull on the belt tending to swing the side plates on their pivots and lift their front ends, and tine-equipped bars carried by the chains.
8. In a loader of the kind described, the combination with a truck including front wheels, a main frame and a supplemental frame having its rear end hinged to the intermediate portion of the main frame, said 85 front wheels being journaled on the supplemental frame, posts on the supplemental frame, a lifting device including a rocking element pivoted to the post and operative to lift the main frame, and a pickup device 90 carried by the supplemental frame.
9. In a loader of the kind described, the combination with a truck including front wheels, a main frame and a supplemental frame having its rear end hinged to the intermediate portion of the main frame, said 95 front wheels being journaled on the supplemental frame, posts on the supplemental frame, a lifting device including a rocking element pivoted to the post and operative to lift the main frame, side plates pivoted to 100 the supplemental frame for vertical swinging movement, means supporting the side plates from the main frame in different positions on their pivots, and a pickup device 105 carried by the side plates.
10. In a loader of the kind described, the combination with a truck including front wheels, a main frame and a supplemental frame having its rear end hinged to the intermediate portion of the main frame, said 110 front wheels being journaled on the supplemental frame, posts on the supplemental frame, a lifting device including a rocking element pivoted to the post and operative to lift the main frame, side plates pivoted to 115 the supplemental frame for vertical swinging movement, means supporting the side plates from the main frame in different positions on their pivots, and a pickup device 120 carried by the side plates.
11. In a loader of the kind described, the combination with a truck including front wheels, a main frame and a supplemental frame having its rear end hinged to the intermediate portion of the main frame, said 125 front wheels being journaled on the supplemental frame, posts on the supplemental frame, a lifting device including a rocking element pivoted to the post and operative to lift the main frame, side plates pivoted to 130 the supplemental frame for vertical swinging movement, means supporting the side plates from the main frame in different positions on their pivots, and a pickup device carried by the side plates.

the supplemental frame for vertical swinging movement, means supporting the side plates from the main frame in different positions on their pivots, a pickup device carried by the side plates, and a deck on the supplemental frame with which the pickup device coöperates.

In testimony whereof I affix my signature in presence of two witnesses.

ORRA L. GILLILAND.
